UNITED STATES PATENT OFFICE

2,327,810

VACUUM CLEANER

Joseph A. McAnerney, New York, N. Y., assignor
to Electric Vacuum Cleaner Company, Inc., a
corporation of New York

Application December 23, 1939, Serial No. 311,353

1 Claim. (Cl. 230—232)

The present invention relates to vacuum cleaners of the type in which the suction-producing and dirt-separating means are supported within an enclosing casing.

The object of my invention is to provide an improved construction and arrangement for reducing the noise of operation, and for a consideration of what I believe novel and my invention attention is directed to the following description and the claim appended thereto.

In the accompanying drawing, Fig. 1 is a sectional elevation of a vacuum cleaner embodying my invention; Fig. 2 is a top plan view of the sound absorber showing its relation to the vacuum cleaner casing; Fig. 3 is a sectional elevation of one of the discharge louvers in the casing; Fig. 4 is a fragmentary sectional elevation of the sound absorber; and Fig. 5 is a fragmentary top plan view of the sound absorber.

Referring to the drawing, there is shown a vacuum cleaner having a vertical cylindrical casing 1 supported on casters 2 and provided with a handle 3. At the lower end of the casing is a suction coupling 4 for connection with a conventional flexible hose provided with a suction nozzle. The suction coupling is mounted on a tube 5 extending through the side of the casing and fixed at its inner end to an elbow 6 mounted on a supporting ring 7 fixed to the side walls of the casing. The upper end of the elbow 6 has connected thereto a vertical tube 8 discharging against a cover 9 seated on the upper edge of the casing. With this arrangement the suction hose is connected to the lower part of the vacuum cleaner casing and there is less tendency for the casing to tip as it is pulled about by the suction hose.

Extending through the center of the supporting ring 7 is a casing 10 for a multi-stage centrifugal fan 11 driven by a motor 12 mounted on and depending from the casing. The casing 10 is provided with an outwardly extending flange 13 bolted to the inner edge of a rubber ring 14. The outer edge of the rubber ring is bolted to the inner edge of the supporting ring 7. The rubber ring accordingly provides a resilient support for the motor fan unit. Fixed to the top of the supporting ring 7 is a U-shaped standard 15 supporting a plate 16 having fixed thereto a plurality of brackets 17. Bolted to the brackets 17 are concentric, vertically extending cylinders 18 and 19 of wire mesh, the cylinders being held in spaced relation by spacers 20 surrounding the bolts extending through the bracket 17 and by an annular bead 21 extending between and

5 bolted to the upper ends of the cylinders. The lower end of the cylinder 19 terminates at the brackets 17. The lower end of the cylinder 18 depends below the brackets 17 and around and spaced from the fan casing 10. Extending downward within the upper end of the casing 1 is a cloth bag 22 clamped at its upper end to a metal ring 23 having an outwardly extending flange 24 covered by a rubber bead 25 and clamped between the cover 9 and the upper edge of the casing. The flange 24 is provided with an enlarged portion 26 through which the upper end of the tube 8 extends. Fixed to the lower edge of the ring 23 and depending within the bag 22 and around the cylinder 18 is a frame comprising spaced vertical strips 27 fixed at their lower ends to a metal ring 28. The bag extends downward from the ring 23, below the ring 28 at the lower end of the frame, upward between the frame and the cylinder 18, over the bead 21 and downward within the cylinder 19. The air discharged against the cover 9 by the tube 8 is filtered through the bag and enters the fan casing through inlet openings 29 in the upper end of the fan casing 10. The air is discharged from the fan in an axial direction through and around the motor 12 and out through openings 30 in the motor casing as indicated by the arrows 30a. The air discharged from the fan has a rotational or swirling motion and is discharged axially through the openings 30 with a spiral and generally downward motion.

At the bottom of the casing 1 is a cup-shaped sound absorber or reducer having a circular bottom wall 31 and cylindrical side walls 32 each comprising a plurality of layers of non-metallic sound absorbing material, such as corrugated paper. The bottom walls of the sound absorber fit within a cylindrical recess 33 in a disk 34 bolted to the bottom of the casing 1. The bottom walls 31 of the sound absorber are bolted to the disk 34. The side walls 32 of the sound absorber extend upwardly and have their upper ends presented toward the fan and surrounding and spaced from the fan discharge openings 30. The cylindrical walls 32 of the sound absorber provide an annular space surrounding the motor to which the fan discharges axially. In this space the air has a rotational or swirling motion. The upper ends of the cylindrical walls 32 of the sound absorber are spaced slightly below the fan casing, providing a passage 35 through which air flows from the interior of the sound absorber. The air flowing through the passage 35 is discharged from the casing through louvers 36.

55 The sound absorber produces a marked reduc-

tion in the noise of operation. This reduction is due partly to the fact that the motor 12 is substantially wholly surrounded by walls of sound absorbing material. A further reduction of noise is due to the shape of the sound absorber or reducer which provides a cup-shaped chamber to which the air is discharged axially from the fan with a rotational or swirling motion. In this chamber the air loses some of its rotational motion before flowing to the louvers 36 through the relatively restricted annular passage 35 between the fan and the upper ends of the sound absorber walls 32. From this aspect, the side walls 32 of the sound absorber serve as a baffle separating the air with a high rotational velocity around the motor 12 from the air with a low rotational velocity adjacent the louvers 36. The noise is

further reduced by the fact that the air flowing through the passage 35 flows transverse to the tubular passages 37 between the corrugations in the paper forming the walls 32. The passages 37 function as sound mufflers or absorbers.

What I claim as new and desire to secure by Letters Patent of the United States is:

In combination, a motor, a centrifugal fan driven thereby and discharging axially around the motor, and walls defining a cup-shaped space having an open top spaced from the fan and a discharge passage from and presented to said space between the fan and said top, said walls including a cylinder of a plurality of layers of corrugated paper with the ends of the corrugations presented to said passage.

JOSEPH A. McANERNEY.
